UNITED STATES PATENT OFFICE

CHARLES A. WARDEN, OF HEMPHILL, WEST VIRGINIA, ASSIGNOR TO KINGSTON-POCAHONTAS COAL COMPANY, OF NEW YORK, N. Y., A CORPORATION OF WEST VIRGINIA

COAL-LOADING CONVEYER

Application filed January 17, 1928. Serial No. 247,322.

This invention relates to conveyers and more particularly to an apparatus for transferring loose coal in a mine to the cars in which it is transported from the mine. This 5 application pertains to improvements in the invention of my prior application Serial No. 111,594.

In present-day methods of mining coal, a so-called "Short wall" or "Long wall" mining 10 machine is used to undercut the body of coal. The coal is then shot down and rests in a loose mass of fragments against the face of the seam. This loose coal is usually handled by means of a plurality of conveyers, one conveyer feeding to another and the last conveyer of the series dumping into the cars on the mine track. The use of a plurality of conveyers besides the initial cost and expense of 15 repairs and upkeep involves considerable time and trouble in the handling thereof particularly in moving the conveyers from place to place as required.

It is an object of the present invention to provide a simple and satisfactory unitary 20 conveyer of rugged construction which will facilitate the transfer of coal from the face of the seam to the mine cars and which can be easily and readily manipulated in the mine to remove coal from the desired portion of 25 the seams as mined. Another object of this invention is to provide a sectional conveyer, certain sections of which may be reversed in the mine to work either the right or left side of a seam without changing the position of 30 the dumping end of the conveyer. Still another object is to provide a conveyer that may be adjusted to remove coal from seams at varying heights in the mine walls and may dump the coal at varying altitudes, i. e. the 35 loading end of the conveyer may be raised or lowered to be inserted in seams at varying positions in the vertical walls of the mine and the position of the dumping end of the conveyer may be varied to dump the coal at varying 40 heights.

Other objects and advantages will be apparent from the detailed description taken in connection with the accompanying drawings in which Fig. 1 is a plan view partly broken 45 away to enable the showing of the structure

of the conveyer from end to end, and illustrating a preferred embodiment of this invention; Fig. 2 is a fragmentary side elevation of the conveyer on an enlarged scale as compared with Fig. 1; Fig. 3 is a fragmentary 55 side elevational detail illustrating the mounting for the inclined and boom conveyer sections and showing the mechanism for positioning the boom section; Fig. 4 is a sectional view on the line 4—4 of Fig. 1; Fig. 60 5 is a side elevational detail of a conveyer take-up device; Fig. 6 is a fragmentary side elevation illustrating a modified form of connection between the loading and inclined conveyer sections; Fig. 7 is a diagrammatic plan 65 view illustrating the manner in which the conveyer is used and Fig. 8 is a diagrammatic view on the line 8—8 of Fig. 7 illustrating a 70 method of moving the conveyer under the loose coal.

Referring to Figs. 7 and 8 of the drawings, 1 indicates a coal seam from the face 2 of which a mass 3 of loose coal has been shot down. A plurality of cars 4 are moved upon the mine tracks 5 in the gallery 6 into proper 75 position to receive the coal. The dumping end 7 of a conveyer 8 empties into the mine cars 4 which are advanced intermittently as they are filled. The conveyer 8 hereinafter described in detail is arranged in operative 80 relation to the face 2 and is adapted to be forced by a plurality of jacks 9 which rest against the timbers 10 under the mass 3 of broken coal. If desired an automatic feed for 85 the conveyer may be employed, as for example the feed illustrated in my copending application, Serial No. 247,321 filed January 17, 1928. The conveyer 8 is designed to take up the loose coal and to deliver it directly 90 to the mine cars 4.

The conveyer 8 preferably comprises a plurality of sections connected by section splicers 11. The loading end of the conveyer comprises a section 12 which includes a top plate 14 (Fig. 4) provided with a sloping face 15 95 and a flattened portion 16 resting on or secured to a bottom plate 13 having integral therewith or fastened thereto a side plate 17. A chain guide 18 is secured as by riveting or welding to the side plate 17 and is ar- 100

ranged to fit in groove 19 in flights 20 of a chain 21 hereinafter described. The chain guide 18 preferably extends through substantially the entire length of the conveyer. Bottom plate 13 extends in front of flattened portion 16 of top plate 14 as shown at 22 forming a wedge-shaped bit facilitating the introduction of the conveyer beneath the body of coal.

10 Section 25 of conveyor 8 includes a top plate 26, a bottom plate 27 and a side plate 28 preferably constructed and arranged in an identical manner with the construction of the top, bottom and side plates 14, 13 and 17. The 15 plates of this section are in longitudinal alignment with the corresponding plates of section 12 of the conveyer.

Section 30 is formed of side plate 32, top plate 33 and bottom plate 34 arranged and secured as hereinbefore described, in connection with side plate 17, top plate 14 and bottom plate 13. Sloping face 35 of top plate 33 extends throughout only a portion of the length of the top plate as indicated at 36 and the top plate gradually widens as shown at 31 until it is of substantially the same width as the bottom plate 34. A plate 37 connects the inclined portion 36 of top plate 33 with the bottom plate 34 preventing coal or other material from entering at this point in the space between the top and bottom plates 33 and 34. The top, bottom and side plates 33, 34 and 32 are in longitudinal alignment with the corresponding plates of conveyer section 25 and also gradually incline upwardly as indicated at 38. Preferably a side plate 39 is provided at the side of the conveyer opposite from the side plate 32 and extends from the inclined plate 37 to the end of the conveyer section 30.

40 Conveyer section 40 comprises top and bottom plates 41, 42, secured in spaced relation on the side plates 43, 44, inclined upwardly and extending in longitudinal alignment with the top and bottom plates 33, 34 of conveyer section 30. The side plates 43, 44 also extend in longitudinal alignment with the corresponding plates of section 30 of the conveyer. The end 47 (Fig. 3) of this conveyer section is preferably provided with an extending arm 45 which is pivotally mounted on a cross rod or shaft 46 supported in the structural frame work for section 40 of the conveyer as indicated generally by the reference numeral 48.

45 The boom conveyer section 50 comprises top and bottom plates 51, 52 in longitudinal alignment with the top and bottom plates 41 and 42 and side plates 53, 54 in alignment with the corresponding side plates of the conveyer section 40. Side plates 53, 54 have depending therefrom arms 55 which are pivotally mounted on cross rod 46. A member 56 extends from the base of the boom conveyer section as from the side plate 53 and has a

cam or inclined surface 57 which is arranged to be engaged by a rack 58 slidably mounted in the frame support 48. The rack is preferably actuated manually through a crank or hand lever 59 keyed or otherwise secured to a shaft 60 rotatably mounted in bearings (not shown) on the frame support 48. A pinion 61 is keyed or otherwise secured to shaft 60 and is arranged to mesh with rack 58. It is evident that by turning the hand lever 59 either clockwise or counter-clockwise, pinion 61 will be rotated to move the rack either forward or backward and correspondingly elevate or lower the boom conveyer section 50, as indicated by the full and dotted lines Fig. 2. The boom conveyer section is held in desired position by the mine car wall on which it rests or by some suitable support placed thereunder. If desired a threaded rod may be fastened to the base of this conveyer section and this rod may cooperate with a nut member to elevate or lower the boom conveyer section and hold it in the desired position. Such a structure is illustrated in my copending application Serial No. 247,321 hereinbefore mentioned.

50 Mounted adjacent the conveyer section 12 and preferably bolted or otherwise secured thereto is a chain take-up and sprocket supporting device 65. This device includes a cast or sheet metal housing 66 in which is mounted a shaft 68. A sprocket 70 is mounted on shaft 68. Screw threaded rods 69 are arranged to engage the shaft 68 and by turning the threaded rods the shaft and sprocket thereon is moved to take up the slack in the chain 21.

55 At the end of the boom conveyer section 50, a shaft 71 is mounted in bearings 72 and has sprockets 73, 74 secured thereon. A shaft 75 has threaded openings 76 in the ends thereof in which are mounted right and left screw threaded rods 77 passing through the supporting plates 78 and nuts 79 adjacent plates 78. The plates 78 are bolted or otherwise secured to the side plates of conveyer section 30. The shaft 75 has mounted thereon a sprocket 79.

60 The chain 21 is disposed over sprockets 70 on shaft 68 and sprocket 73 on shaft 71. Flights 20 are secured at intervals to the chain 21 and are movable therewith along the top plates 14, 26, 33, 41, 51 of the conveyer toward the sprocket 73. After passing over the sprocket 73 the flights return with the chain beneath the top plates over the bottom plates 52, 42, 34, 27 and 13 to the opposite end of the conveyer. The flights are thus adapted to move the coal which falls upon the top plates 14, 26 and 33 towards the inclined portion of the conveyer.

65 A second chain 80 having a plurality of flights 20 secured at intervals thereto passes over the sprocket 74 on shaft 71 and sprocket 79 on shaft 75. The flights 20 on chain 80

face flights 20 of chain 21 and cooperate therewith to push the coal along the inclined top plate 41 on to the top plate 51 of the boom conveyer section 50 and discharge it from the boom conveyer section directly to the mine cars as illustrated in Fig. 7.

Each of the flights 20 of chains 80 and 21 is provided with a U-shaped section 82 (Fig. 4) adapted to straddle the chain and a rectangular flight portion 83 secured to or integral with the U-shaped section 82. This structure permits the even distribution of the load to the chain.

Chains 80 and 21 are driven from the motor 85 through a speed reducer 86 having shaft 87 provided with a sprocket 88 over which travels a drive chain 89. Chain 89 also travels over a sprocket 90 on shaft 92 journaled in the frame 48. At the other end of shaft 92 (Fig. 1) is a sprocket 93 which has a drive chain 94 travelling thereover. Chain 94 also passes over sprocket 95 on the end of shaft 71 thereby rotating this shaft and sprockets 73, 74 thereon, thus driving chains 80 and 21.

In the modified form of my invention shown in Fig. 6 the conveyer sections 30 and 25 are shown pivotally connected by means of pivot pin 90'. This construction permits movement of the loading end 91 of the conveyer about pivot pin 90', and also permits movement of the conveyer about shaft 46 as a pivot so that the loading end of the conveyer can be positioned at varying heights to remove coal from seams at varying heights in the vertical walls of the mine.

Section 30 of the conveyer is preferably made in right and left hand units so that by the insertion of the proper unit, by reversing sections 12 and 25 and changing the position of chains 80 and 21 the conveyer may be used to work either the right or left hand side of a seam. When it is desired to work on the opposite side of the seam to that worked, the chain take-up device 65 is detached from the conveyer section 12, this section and the adjacent section 25 reversed in the seam, section 30 replaced by an appropriate corresponding unit and the chains 80 and 21 positioned on the drive sprockets. It will be noted that to reverse the conveyer it is unnecessary to move sections 40 and 50 of the conveyer.

While I have described the conveyer as preferably constructed of a plurality of sections, it is understood that this invention is not limited thereto and includes conveyers constructed of one or more units or conveyers having the sections combined, as for example sections 12, 25, 30 and 40 formed as a single unit and boom conveyer section pivotally connected thereto.

The structure of the conveyer as herein described is simple and it can be constructed and operated at a relatively low cost. It is efficient in operation and permits the re-

moval of the loose coal rapidly and directly to the mine cars so that the face of the seam is exposed for further operation within a comparatively short time and additional conveyers are unnecessary for the efficient removal of the coal to the mine cars. The parts of the conveyer may be of rugged construction suitable for the rough usage to which it is subjected and as there are few parts these are not likely to break.

In the preferred structure of the conveyer as illustrated and described herein, various changes can be made in the details thereof and this invention is not to be limited to the structure disclosed but only by the scope of the appended claims.

What is claimed is:

1. In a conveyer, the combination of a plate having a longitudinal material receiving portion and a longitudinal loading edge substantially co-extensive with the length of said plate and the loading portion of the conveyer, said loading edge being arranged to be moved under the material to be transported to force the material onto said material receiving portion of the plate, an inclined plate in longitudinal alignment with the material receiving portion of the first mentioned plate and arranged to receive said material from the first mentioned plate, a material receiving plate in longitudinal alignment with said inclined plate and arranged to receive the material from the inclined plate, flights superposed on said plates, means connected to the flights and to a source of power to advance the flights longitudinally of the plates to move the material therealong and means for adjusting the position of the inclined plate with respect to the first and third mentioned plates.

2. In a conveyer, the combination of a plate having a longitudinal material receiving portion and a longitudinal loading edge substantially co-extensive with the length of said plate, said loading edge being arranged to be moved under the material to be transported to force the material onto said material receiving portion of the plate, an inclined plate in longitudinal alignment with the material receiving portion of the first mentioned plate and arranged to receive said material from the first mentioned plate, a material receiving plate in longitudinal alignment with said inclined plate and arranged to receive the material from the inclined plate, a chain running the length of said plates disposed on one side thereof, a second chain disposed along the opposite side of said inclined and material receiving plates, means for driving the chains in a vertical plane and a plurality of flights secured to the chains and movably thereby along said plates.

3. In a conveyer, the combination of a plurality of sections comprising a reversible

plate section adapted to be moved under the material to be transported, a plate section arranged to be placed in longitudinal alignment with said reversible plate section, a plate section adapted to receive material, a chain having flights thereon extending along one side of said sections, a second chain having flights thereon facing the flights of said first mentioned chain and extending along the other side of said second mentioned plate section and said material receiving plate section.

4. In a machine for loading coal in a mine, a conveyer section comprising top and bottom plates in spaced relation, the top plate having a sloping face forming with the bottom plate, a wedge shaped longitudinal edge extending parallel to and substantially the length of the pile of coal shot down from the seam in the mine, a side plate positioned along said bottom plate and forming a side wall for said top and bottom plates, an inclined conveyer section comprising inclined side, top and bottom plates disposed in longitudinal alignment with the side, top and bottom plates of the first mentioned conveyer section, a boom conveyer section pivoted to said inclined conveyer section and comprising a base and side plates disposed in longitudinal alignment with the top and side plates of said inclined conveyer section, a chain having rectangular flights at spaced positions thereon disposed along one side of said conveyer sections, a second chain having rectangular flights at spaced positions thereon disposed in cooperative relation with the flights of the first mentioned chain, said second chain being disposed along the other side of the inclined and boom conveyer sections, means for moving the first mentioned chain along said top plates and the base plate of the boom conveyer section below said base plate and through the space between said top and bottom plates, means for moving the second chain along the top plate of the inclined conveyer section over the base plate beneath the base plate and through the space between the top and bottom plates of the inclined conveyer section, and means moving said boom conveyer section about its pivot.

In witness whereof, I have hereunto set my hand.

CHARLES A. WARDEN.
